[57] CLAIM

The ornamental design for a chair, as shown and described.

DESCRIPTION

FIG. 1 is a perspective view from the front and one side of a chair showing my design;

FIG. 2 is a perspective view from below as seen from the rear and from the opposite side as compared with FIG. 1; and,

FIG. 3 is a side elevational view, the opposite side being a mirror image thereof.

FIG.2FIG.1

U.S. Patent

Aug. 2, 1988
